(57) **CLAIM**

The ornamental design for a toy robot as shown and described.

DESCRIPTION

FIG. 1 is a front perspective view of a toy robot showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of area 9 indicated in FIG. 2 thereof.

The evenly-spaced broken lines throughout the drawing figures depict portions of the toy robot that form no part of the claimed design; the dot-dot-dash broken lines in FIG. 8 illustrate boundaries of the claimed design; the short dash-long dash broken lines in FIGS. 2 and 9 annotate portions of the figures shown enlarged; all broken lines form no part of the claimed design.
